UNITED STATES PATENT OFFICE

2,316,610

FREQUENCY CONVERTER

William W. Moe, Bridgeport, Conn., assignor to
 General Electric Company, a corporation of
 New York

Application July 24, 1941, Serial No. 403,799

8 Claims. (Cl. 250—20)

My invention relates to frequency converters such as are commonly used in radio receivers to convert the frequency of received oscillations to oscillations having a common or intermediate frequency.

It has for one of its objects, to effect certain improvements in such converters with respect to means for maintaining proper voltage at the converter of the frequency of the local oscillator over the range of frequencies to be received.

Another object of my invention is to provide an improved coupling arrangement between the local oscillator and converter to transfer voltage to the converter of constant intensity at all frequencies over which the oscillator is tunable.

Still another object of my invention is to effect certain improvements in the circuit of the local oscillator whereby its intensity of oscillations generated may be maintained at desired values at different parts of the tuning range.

The novel features which I believe to be characteristic of my invention are set forth with particularity in the appended claims. My invention, itself, however, both as to its organization and method of operation together with further objects and advantages thereof may best be understood by reference to the following description taken in connection with the accompanying drawing in which the single figure represents an embodiment of my invention.

Referring to the drawing, I have represented therein an antenna 1 arranged to intercept oscillations to be received and which is coupled by means of a transformer 2 to the input circuit of an electron discharge converter 3. Oscillations generated by the local oscillator 4 are also supplied to the input circuit of the converter 3 to combine with the received oscillations and produce in the output circuit of the converter oscillations of constant frequency for all frequencies to be received. The output circuit of the converter 3 is represented by the rectangle 5 which may comprise the intermediate frequency amplifiers and selective circuits of the receiver in which my invention is incorporated. Since these circuits are of conventional construction they require no description here.

Operating potential for the anodes of the discharge devices 3 and 4 may be considered as included within the rectangle 5 and supplied to the anodes of these devices through conductors represented by the connecting lines on the drawing.

The anode of the discharge device 4 is connected to ground through a large by-pass condenser 6 and thence through a frequency deter-

mining circuit 7 and grid condenser 8 to the control electrode of this discharge device. The circuit 7 comprises an inductance which may comprise the series connected sections 9, 10 and 11 and which comprises capacitances 12 and 13. The condenser 12 may be variable for tuning the oscillator over the desired band of frequencies. It is connected across the total inductance 9, 10, and 11 of circuit 7. Condenser 13 may be a fixed 10 condenser or one that is variable for purposes of initial adjustment. It is connected across inductances 9 and 10 of circuit 7.

The tuned input circuit of the converter 3 comprises the secondary winding 15 of the transformer 2, which is connected between the control electrode 14 of the converter and a point on the oscillatory circuit 7 between inductances 9 and 10, and it also comprises the tuning condenser 16 connected between the control electrode 14 and ground, this tuning condenser being arranged to be uncontrolled with condenser 12 of the oscillator by means represented by the dotted line 17.

The converter 3 is provided with the usual 25 cathode bias resistor 18 which is shunted by the by-pass condenser 19 at frequencies to be considered.

It will be seen that as thus connected, that portion of the frequency determining circuit 7 of 30 the local oscillator comprising the inductances 10 and 11 is included in the tuned circuits 15, 16 of the converter 3 in series with the condenser 16 and the inductance 15. That is, the tuned input circuit of the converter 3 comprises the inductance 15, inductances 10 and 11 and the tuning condenser 16, the latter resonating at signal frequencies with the inductances 15, 10 and 11.

In operation the tuned circuit comprising the inductances 15, 10 and 11 and condenser 16 may 40 be arranged to be tunable over a frequency band extending from 40 to 50 megacycles, for example, by variation of the tuning condenser 16. The oscillator 4 may be tunable over a range of from 30 to 40 megacycles by variation of the tuning condenser 12. That portion of the oscillations generated by oscillator 4 which appears upon inductances 10 and 11 is supplied through inductance 15 between the grid 14 and cathode 20 of the converter whereby they combine with the received oscillations to produce in the output circuit 5 of the converter, an intermediate frequency of ten megacycles for any frequency received on the antenna.

It is desired, in order to obtain efficient frequency conversion in the converter tube 3, that

the intensity of oscillations supplied from the local oscillator to the converter grid 14 be substantially constant throughout the tuning range. The intensity of these oscillations, however, is affected by a number of causes. For example, if the frequency is increased the difference between the frequencies to which the tuned circuit of the converter and that of the local oscillator are tuned becomes a smaller part of the total frequency. Thus the circuits are tuned nearer to the same frequency on a percentage basis at the upper end of the band than at the lower end of the band. This means that the transfer of oscillations from the local oscillator through the network comprising the inductance 15 and the condenser 16 is more efficient at the upper end of the band than at the lower end of the band, thereby tending to increase the voltage between the control electrode 14 and cathode 20 of the converter in the higher frequencies. At the same time, as is characteristic of most oscillator circuits, the oscillator 4 oscillates more strongly at the higher frequencies than at the lower frequencies, thereby likewise tending to increase the intensity of oscillations supplied to the converter. These oscillations, however, are supplied from the two inductances 10 and 11. These inductances are so arranged in the circuit with respect to condensers 12 and 13 that the voltage thereon may be adjusted to vary in proper relationship to maintain the voltage between control electrode 14 and cathode 20 substantially constant over the band.

In initially adjusting the system for operation the condensers 16 and 12 may be adjusted for operation at the high frequency end of the band. At this frequency very little current flows in condenser 12 or inductance 11. The inductance 10 may then be adjusted to produce oscillations between the control electrode 14 and cathode 20 of the proper intensity at the highest frequency in the band. The condensers 16 and 12 may then be adjusted for operation at the lowest frequency in the band. This tends to reduce the voltage on coil 10 because of the fact that the oscillator oscillates less strongly at the low frequencies than at the high frequencies. However, because of the increase in current in condenser 12, as the capacity is increased, the voltage on inductance 11 through which this current flows also increases. This inductance 11 may then be adjusted to produce the proper voltage between the control electrode 14 and cathode 20 of the converter. This adjustment does not, to any substantial extent, affect the first adjustment at high frequencies because very little current flows in capacitance 12 at the high frequencies. If it does affect it, condensers 16 and 12 may again be adjusted for high frequency and the inductance 10 readjusted, these adjustments being repeated until proper operation over the band is secured. When thus adjusted the system produces substantially constant voltage between the control electrode and cathode of the converter throughout the range of frequencies to be received and this is true notwithstanding the more efficient transfer of voltage to the control electrode through the network 15, 16 at the high frequencies than at the low frequencies.

Of course, while in the drawing I have represented the various inductances in the conventional form of coils, in actual practice these inductances may be of any desired form. It has been found that the inductances 10 and 11 may comprise merely the inductances of certain

lengths of straight wire. In one device constructed in accordance with my invention the inductance 10 comprised a wire of about an inch in length and the inductance 11 comprised a wire of about two inches in length. The arrangement which I have described possesses very desirable advantages when utilized at high frequencies such as those mentioned and are also very useful and desirable at lower frequencies.

10 While I have shown a particular embodiment of my invention, it will be understood that I do not wish to be limited thereto since different modifications may be made both in the circuit arrangements and in the instrumentalities employed and I contemplate by the appended claims to cover any such modifications as fall within the true spirit and scope of my invention.

What I claim as new and desire to secure by Letters Patent of the United States, is:

20 1. The combination, in a frequency converter for high frequency receivers, of a signal input circuit, a tuned local oscillator circuit, said circuits including an inductive impedance in common, a tuning condenser in the local oscillator circuit in series with said impedance, and means for increasing the current in the impedance as the capacity of said tuning condenser increases thereby to increase the voltage supplied from the local oscillator to said signal input circuit as the 30 frequency of the local oscillator is reduced.

2. The combination, in a frequency converter for high frequency receivers, of a signal input circuit, a tuned local oscillator circuit, said circuits including an inductive impedance in common, a tuning condenser in the local oscillator circuit in series with said impedance, said oscillator having a tendency to produce oscillations reducing in intensity as the capacity of said tuning condenser is increased to reduce the frequency of oscillations produced, and means utilizing the reduced impedance of said tuning condenser for increasing the current in said impedance thereby to maintain the voltage supplied from said oscillator to said signal input circuit within a narrow range of variation over the range of frequencies controlled by said tuning condenser.

3. The combination, in a frequency converter for high frequency receivers, of a signal input circuit, a local oscillator circuit, said circuits having two series connected impedances in common, means to tune said local oscillator circuit over a range of frequencies, the voltage on one of said impedances tending to vary during such tuning, and means to vary the voltage on the other of said impedances to compensate for variations in voltage produced on said one impedance during such tuning thereby to maintain the voltage supplied to said input circuit within a narrow range of variation.

4. The combination, in a frequency converter for high frequency receivers, of a signal input circuit, a local oscillator circuit having two series connected impedances and a variable tuning condenser, the voltage on one of said impedances varying as the tuning of said circuit is varied by variation of said tuning condenser, means to vary the voltage on the other of said impedances in response to variation of said tuning condenser to compensate for variation in voltage on said one impedance, and means to supply the combined voltage of said two impedances to said input circuit.

5. In combination, an electron discharge de-

vice having an anode, a cathode, and a control electrode, an inductance between said anode and control electrode having an intermediate point connected to said cathode, a plurality of condensers connected between said control electrode and points on said inductance between said anode and cathode, the condenser connected nearest the anode being variable over a range of frequencies whereby said device generates oscillations at a frequency determined by said condenser, and an output circuit for the oscillations produced connected between said anode and a point on said inductance.

6. In combination, an electron discharge converter having a tuned input circuit variable over a range of frequencies connected between its input electrodes, a local oscillator having a frequency determining circuit tunable in unison with said tuned input circuit over a corresponding lower range of frequency whereby the percentage difference in frequencies to which said circuits are tuned reduces as the frequency increases, the inductive and capacitive branches of said tuned input circuit being connected in series across an inductive impedance in said frequency determining circuit whereby voltage is supplied from said frequency determining circuit to said input electrodes, and means responsive to variation in tuning of said frequency determining circuit to vary the voltage on said inductive impedance to maintain substantially constant the voltage between said electrodes notwithstanding increased step-up of voltage by action of said inductive and capacitive branches when said percentage difference in frequencies of said circuits is reduced.

7. In combination, an electron discharge converter having a tuned input circuit connected between its cathode and input electrode, a local electron discharge oscillator having an anode, a cathode, and a control electrode, said anode being connected to said control electrode through an oscillatory circuit comprising shunt connected inductance and variable capacity and to said cathode of said converter, said input electrode of said converter being connected through the inductance of said tuned input circuit to an intermediate point on said oscillatory circuit, and means responsive to variation of said variable capacity to maintain constant voltage from said local oscillator between said input electrode and cathode of said converter over a wide range of frequencies to which said circuits may be tuned.
8. In combination, an oscillating circuit including a variable tuning condenser, a load circuit, said oscillating circuit being arranged to supply oscillations to said load circuit, an inductive impedance common to said circuits, said oscillating circuit having a tendency to produce oscillations undesirably reducing in intensity as the capacity of said tuning condenser is increased to reduce the frequency of oscillations produced, and means for increasing the current in said impedance as the capacity of said tuning condenser increases thereby to vary the voltage supplied from said oscillating circuit to said load circuit in a sense to compensate for the undesirable reduction in intensity of said oscillations as the frequency of said oscillating circuit is reduced.
